SHEET MATERIAL DISPENSER

Erwin B. Bahnsen, Hinsdale, Ill., assignor, by mesne assignments, to Georgia-Pacific Corporation, Portland, Oreg., a corporation of Georgia

Filed Apr. 25, 1963, Ser. No. 275,593
6 Claims. (Cl. 225—16)

This invention relates to a dispenser for sheet material such as paper toweling. More particularly, the invention relates to improvements in a wall type cabinet for dispensing lengths of paper or other sheet material from rolls of material.

An important object of the invention is to provide a relatively simple, compact and economical dispenser which dispenses sheet material conveniently and reliably.

A particular object is to provide a dispenser which presents sheet material to the user for grasping the end of the material and pulling to sever a length of material, and which functions to sever the material properly when it is pulled in any of several possible normal ways.

Another object is to provide a dispenser provided with safeguards against tampering, and particularly, which reduces the possibilities for jamming the dispenser.

An additional object is to provide a dispenser which includes structure for supplying sheet material simultaneously from a full roll and from a stub roll thereon, to use up the latter after the dispenser is refilled.

A further object is to provide a dispenser having improved mounting means for the parts, and which may be assembled and disassembled easily and rapidly. An accompanying object is to provide a dispenser constructed of but a small number of parts.

Another object is to provide a dispenser including roller dispensing means, which embodies improvements in the mounting of the roller means and other parts, including improvements in the construction and arrangement of bearings or the like for the roller means.

Another particular object is to provide a new and improved sleeve bearing which cooperates in accomplishing the foregoing and other objects.

These and other objects, advantages, and functions of the invention will be apparent on reference to the specification and to the attached drawings illustrating a preferred embodiment of the dispenser, wherein like parts are identified by like reference symbols in each of the views, and wherein:

FIGURE 1 and FIG. 2 are, respectively, front and side elevational views of the dispenser;

FIG. 3 is an enlarged side elevational view of the dispenser with the casing thereof lowered;

FIG. 4 is a sectional and elevational view of the dispenser, taken on line 4—4 of FIG. 3;

FIG. 5 is a sectional and plan view thereof, taken substantially on lines 5—5 of FIG. 7;

FIGS. 6 and 7 are, respectively, enlarged fragmentary front and side elevational detail views of one corner of the dispenser, corresponding respectively to the views of FIGS. 1 and 2;

FIG. 8 is an enlarged side elevational view similar to FIG. 3 but with the casing removed, and also illustrating sheet material being delivered simultaneously from a full roll and from a stub roll in the dispenser;

FIG. 9 is an enlarged fragmentary sectional and elevational view taken on line 9—9 of FIG. 8, illustrating particularly a guard element and a knife mounted thereon;

FIG. 10 is an enlarged fragmentary sectional view taken on line 10—10 of FIG. 4, with parts broken away;

FIG. 11 is an enlarged broken side elevational view of a drive roller assembly in the dispenser;

FIG. 12 is an exploded broken side elevational view of

2

the drive roller assembly, with split rings thereof being shown in perspective;

FIG. 13 is an enlarged and elevational view of a sleeve bearing employed in the drive roller assembly;

FIG. 14 is a side elevational view of the components of the bearing illustrating the manner in which the bearing is inserted into wall openings; and

FIG. 15 is a side elevational view of the bearing in its ultimate position in the openings.

Referring to the drawings, especially FIGS. 1—5, the invention provides improvements in a wall type dispenser or dispensing cabinet 10 for rolled sheet material. The dispenser includes a frame 12, a casing 14 pivotally mounted on the frame, and delivery apparatus 16 mounted on the frame. While the illustrative embodiment constitutes a preferred form of the invention, it will be understood that the improvements provided by the invention may be employed in other environments.

The frame 12 includes a normally horizontal bottom wall 18, a normally vertical back wall 20, and a pair of like normally vertical spaced parallel opposite side walls 22. The several walls are formed integrally from one piece of sheet metal or the like. The side walls each include a support plate or member 24 integral with the bottom wall 18 and extending upwardly therefrom. Each of the side walls also includes a panel 26 integral with the back wall 20 and extending forwardly therefrom. A flange 28 is integral with the upper margin of the back wall and extends forwardly therefrom to provide a rim thereon.

It is a feature of the invention that the frame 12 may be formed of one piece of material which is also fabricated to perform a number of other functions. Referring especially to FIGS. 5 and 8, a pair of spaced parallel upstanding tabs 30 are struck out from the bottom wall 18, leaving openings 32 of the same shape in the wall. The tabs are near to and spaced from respective side walls 22, and they serve as locators and spacers for a stub roll 32 of sheet material resting on the bottom wall. The bottom and back walls and the tabs provide a receptacle or compartment 33 for the stub roll.

Referring also to FIG. 4, hook portions 34 are formed in the back wall 20, in enlarged openings 36. A yoke assembly of a yoke 38 and hubs 40 is pivotally supported on the back wall by the hook portions. The yoke includes a crossbar 40 pivotally held by the hook portions, and side arms 42 which rotatably support the hubs at the outer ends of the arms. The hubs include inwardly extending rims 44 which are received within the usual core tube of a roll 46 of paper toweling or other sheet material. The rims frictionally engage the inner surface of the core tube, so that the roll is rotatably suspended by the yoke arms. The back wall 20 also includes a pair of upper keyhole type mounting slots 48 adjacent to the respective hook portion openings 36, and three mounting slots 50 in the lower half of the wall.

The support plate 24 of each side wall 22 is provided with a circular mounting opening 52 in its upper front portion, and a rectangular opening 54 adjacent to the bottom wall 18. An inwardly and forwardly extending spring mount 56 is stamped from the side plate and leaves a correspondingly shaped opening therein. A retaining flange 58 is struck from the support plate at its upper margin, leaving a corresponding recess therein, and the flange extends inwardly perpendicular to the support plate.

Referring to FIGS. 4, 5 and especially 10, a paper guide element 60 is mounted on the bottom wall 18 and extends from one support plate 24 of a side wall 22 to the opposite support plate. The guide element is spaced forwardly from the back wall 20 and forms the front bound-

ary of the stub roll receptacle 33. The guide element also defines a delivery zone or compartment on the opposite or front side thereof, in which the delivery apparatus 16 is mounted. The guide element is constructed in one piece of sheet metal or other suitable material. It includes a guide plate 62 commencing at an upper end thereof with a downwardly and rearwardly inclined section 64. An arcuate section 66 extends downwardly and forwardly therefrom. The plate terminates in a reversely curved lip 68, which extends downwardly in front of the forward edge of the bottom wall 18. An integral horizontal shoulder or ledge 70 extends rearwardly from the inclined section 64 at the top of the guide plate. Two horizontal support strips 72 extend integrally from the rear of the shoulder 70, adjacent to the respective support plates 24. A vertical baffle plate 74 extends integrally from the rear of the shoulder 70, across the frame from one support strip 72 to the other, as seen in FIGS. 4 and 5.

A guard element 76 is mounted in the delivery zone at the front of the frame 12 and extends between the side wall support plates 24, on the front side of the guide element 60 and spaced therefrom. The guard element includes an upwardly and rearwardly inclined guard plate or partition 78 having integral upstanding tabs 80 on either side secured to the respective side wall support plates 24. The rear marginal section of the guard plate is bent upwardly and slotted to provide inclined integral rectangular guard fingers 84 in aligned spaced relation therewith. The guard plate is spaced above the bottom wall 18 and the lower portions of the guide plate 62, and its rear margin is spaced forwardly from the upper section 64 of the guide plate. A flange 82 is integral with the guard plate and extends upwardly therefrom along its front edge. The guard plate 78 and the guide plate 62 together from a movement path 86 for conducting sheet material out of the dispenser.

Referring especially to FIGS. 9 and 10, a cutting element 88 is mounted on the lower side of the guard plate 78 along its rear marginal section. The cutting element includes a strip 90 secured to the guard plate, and an integral knife blade 92 depending therefrom below the guard fingers 84 and slightly inclined to the rear. The knife blade includes a plurality of saw teeth composed of short teeth 94 and spaced apart long teeth 96. The teeth are regularly arranged along the blade, with the short teeth arranged in pairs of adjacent teeth and a long tooth following each pair of short teeth. The knife blade 92 extends substantially completely across the frame in spaced relation to the upper inclined section 64 of the guide plate. The two form a relatively narrow downwardly directed channel 98 constituting the initial portion of the movement path 86, for downward movement of sheet material therebetween. The downward and rearward inclination of the upper guide plate section 64 is greater than the corresponding inclination of the knife blade 92, so that the sides of the resulting channel 98 diverge in the direction of movement of sheet material, for a purpose described subsequently. The knife blade is arranged for the user to pull sheet material outwardly therefrom in a different direction, placing the material under tension, for severing a length of material thereby.

Referring especially to FIGS. 4, 5 and 11-15, a drive roller assembly 100 is mounted on the side wall support plates 24 and extends across the frame 12 in the delivery zone above the guard element 76. The assembly includes a cylindrical drive rod 102 which terminates at one end in a stub shaft 104 of reduced diameter, and at the other end in a tubular portion having an internal cylindrical cavity 106. The tubular end terminates in a pair of helically cut clutch portions 108. Rubber tires 110 or the like are fixedly secured on the rod 102 in equi-distantly spaced relation therewith. The assembly includes a crank 112 having a handle 114 and a shaft portion 116.

The shaft portion is received within the cavity 106 in the rod 102. A transverse hole 118 is provided in the shaft portion, and a clutch pin 120 is received therein in frictional engagement. A compression coil clutch spring 122 is mounted around the shaft portion 116, between a pair of washers 124. A friction coil brake spring 126 having a hook end 128 is mounted around the drive rod 102, adjacent to the end having the stub shaft 104. A sleeve bearing 130 is located at each end of the assembly for mounting purposes. One bearing is mounted on the stub shaft 104, and the other bearing is mounted on the shaft portion 116 of the crank. Each bearing is composed of two identical longitudinal sections 132, each of which constitutes one-half of the bearing, as described in detail hereinafter. The bearing sections are secured together by split rings 134.

The drive roller assembly 100 is rotatably mounted on the side wall support plates 24. The drive roller comprising the drive rod 102, the crank 112, and the tires 110 is journaled at opposite ends in the support plate mounting openings 52. A sleeve bearing 130 is disposed in each mounting opening and interposed between the stub shaft 104 or the crank shaft portion 116, as the case may be, and the surrounding support plate 24 at the corresponding side of the frame 12.

As seen in FIGS. 4, 5 and 8, the drive roller assembly 100 is mounted over the rear edge of the guard plate 78, below a roll 46 of the sheet material supported by the yoke assembly 38 and spaced from the roll, and disposed a short distance forwardly of the center or axis of the roll. The roller assembly is arranged with the tires 110 extending into the spaces between the guard fingers 84. The hook end 128 of the brake spring 126 depends from the rod 102 and is hooked over the lower edge of the knife blade 92, as seen in FIG. 10. The clutch spring 122 biases the clutch pin 120 against the tubular end of the drive rod 102, for engagement of the pin with one of the clutch portions 108. When the crank 112 is turned in the clockwise direction, as viewed in FIG. 8, the drive rod and the tires 110 thereon turn in the same direction. In the event that the crank is turned in the opposite direction, the clutch pin rides over the clutch portions, and the brake spring 126 prevents the drive rod from turning.

Referring particularly to FIGS. 5 and 10, an idler roller assembly 160 is movably mounted in the delivery zone on the guide element 60, which cooperates with the side wall support plates 24. The assembly includes a cylindrical idler or pinch roller 162 mounted above and near to the upper guide plate section 64 and the shoulder 70, and movable or shiftable relative thereto. The idler roller includes integral stub shaft portions 164 extending from opposite ends thereof. Resilient mounting means are provided for yieldably holding the idler roller against the tires 110 of the drive roller, with the roller axes parallel and substantially lying in one horizontal plane. The mounting means includes holders or bearing blocks 166 at respective ends of the idler roller 162. The holders preferably are constructed of a plastic bearing material such as nylon, but they may be constructed of other material. Each holder has a transverse groove 168 on one end, and each groove receives one of the idler roller stub shafts 164 rotatably therein. A longitudinal bore 170 is provided in the opposite end of each holder, and it receives one end of a coil compression spring 172 therein. The opposite end of the spring is received around the free end of the spring mount 56, to hold the spring in place. The holders are slidable on the support strips 72 while rotatably supporting the idler roller, moving forwardly and rearwardly thereon. The holders are further held in place by the adjacent support plates 24 and the retaining flanges 58 extending over the holders, which parts form inwardly opening channels with the support strips. The resulting shifting of the idler roller is accommodated by the guide element shoulder 70 below

the roller, and rearward movement is limited by the baffle 74 behind the roller.

The idler roller 162 is resiliently maintained in line contact with the drive roller tires 110, or sheet material between the rollers, along a transverse line joining the points of contact of the respective curved surfaces. Sheet material is received between the drive and idler rollers from above and is delivered by the rollers therebelow, into the channel 98 of the movement path 86. The tension of the springs 172 is predetermined for delivering the sheet material in this manner, and also to enable the respective rollers to slip on the sheet material when a resistance to delivery is encountered. The provision of the idler roller also serves to minimize wear of the tires 110 when the dispenser is empty.

Referring to FIG. 8, a full roll 46 of sheet material is mounted on the yoke assembly 38 to rotate in a clockwise direction in removing sheet material therefrom. The sheet material is drawn from the rear side of the roll, as indicated at 174. It is inserted between the tires 110 on the drive rod 102, and the idler roller 162. Clockwise rotation of the crank 112 causes the material to travel downwardly and then forwardly in the movement path 86 and be conducted out of the dispenser at the front thereof.

When a stub roll 32 remains at the time of refilling the dispenser, it is transferred to the receptacle 33, and a fresh roll 46 is mounted in the above-described manner. The stub roll rests on the bottom wall 18 between the locator tabs 39, for rotation in the clockwise direction on the wall. Sheet material 176 from the bottom portion of the roll passes over the top of the baffle plate 74 beneath the sheet material 174 from the full roll. The sheets from the two rolls extend together between the drive and idler rollers and into the movement plate 86. It will be observed that the baffle plate 74 extends upwardly beyond the idler roller 162, to guide the material from each roll between the rollers. The sheets from the two rolls are delivered by the rollers simultaneously, so that two sheet lengths are removed at one time by the user. The feed roll 46 is spaced above and out of contact with the stub roll 32, to enable both rolls to rotate freely while material is removed from them. When the stub roll is exhausted, the baffle plate 74 causes the inner end of the sheet material 176 to be stripped from the roll, even though the end may be glued to the core tube thereof.

As seen in FIGS. 1-5, the casing 14 includes a normally horizontal top wall 180, a pair of like normally vertical spaced parallel side walls 182, and a protuberant three-sided front wall 184. The respective casing walls form the top, side and front outer surfaces of the dispenser 10. The frame bottom wall 18 and back wall 20 form the bottom and back outer surfaces.

As seen in FIGS. 6, 7 and 10, the lower edge of the front wall is bent back on itself to form a rounded lip 186 therealong. The lip 186 on the casing and the lip 68 on the guide element 60 define a restricted delivery opening or mouth at the outer end of the movement path 86. As seen in FIG. 3, each of the side walls 182 is provided with a viewing slot 188 therein. The side walls function as support members for the casing, and for this purpose, each wall is provided with a pivot opening 190 (FIGS. 3 and 5) adjacent to its lower front corner. The casing is pivotally mounted at the respective ends of the drive roller assembly 100. The drive rod stub shaft 104 is received within one of the pivot openings 190, and the crank shaft 116 extends through the other pivot opening, with a sleeve bearing 130 also received in each pivot opening and interposed between the drive rod or the crank shaft and the casing wall thereat.

The casing is pivotally movable from a closed or raised position in use, illustrated in FIGS. 1 and 2, over an angle of about 90 degrees to an open or lowered position, illustrated in FIG. 3. In the closed position, the rear margin

of the top wall 180 is supported by the rim 28 along the back wall 20, at which location the casing may be latched or locked by any suitable means, not shown. The dispenser is loaded with a roll 48 of sheet material with the casing in the open position, at which time the sheet material 174 from the full roll, and also sheet material 176 from a stub roll 32 where present, is inserted between the drive roller assembly 100 and the idler roller assembly 160 for delivery as described above.

10 The manner and means for mounting the drive roller assembly 100 and the casing 14 on the dispenser frame 12 represent preferred features of the invention. The sleeve bearing 130 is uniquely constructed for securing the members in proper assembled relationship, and to facilitate 15 assembly and disassembly of the structure. The bearing preferably is constructed of a plastic bearing material such as nylon, but it may be constructed of other material. Referring to FIGS. 11-15, each longitudinal section or half-bearing 132 is transversely arcuate, defining a 20 semicylindrical journal cavity 200 therein. Each half-bearing terminates in two side edges 202. Each side edge includes a substantially planar or straight portion 202a at a wide or enlarged end 204 of the half-bearing. The planar portions of each half lie flat on the companion 25 portions of the remaining half in forming the bearing 130, and they are in a plane with the longitudinal axis of the bearing. Each side edge also includes a curved recessed or relieved portion 202b, which curves inwardly from the planar portion 202a to the remaining narrow or reduced 30 end 206 of the half-bearing. The recessed portions of each half respectively diverge from the companion portions of the remaining half in the assembled bearing, for a purpose described subsequently.

The assembled sleeve bearing 130 includes transverse 35 annular sections of several different diameters. Commencing with the left-hand wide end 204, as viewed in FIGS. 14 and 15, a circular end section is provided on the bearing by mating semi-circular first body portions 208 on the respective half-bearings. The body portions 40 are beveled at their outer edges. The annular bearing section formed thereby has an outer diameter equal to the major diameter of the bearing. A semicircular grooved portion 210 follows on each half-bearing, and the respective portions mate to form a circular externally grooved 45 section of reduced diameter on the bearing. Each half-bearing next is provided with a circular second body portion 212 which together with the corresponding portion on the remaining half forms a circular transverse bearing section having the same diameter as that provided by the 50 first body portions 208. A split ring 134 is received in the transverse groove provided by the grooved portions 210, between the body portions 208 and 212, to secure the bearing halves together on the shaft portions of the drive roller assembly 100 (see FIGS. 11 and 12). The 55 second body portions 212 provide an external bearing surface on which one of the side wall support plates 24 bears around the mounting opening 52 thereon.

Each half-bearing 132 next includes an arcuate transverse grooved portion 214, which together with the corresponding portion on the remaining half provides a circular transverse grooved bearing section representing the minor diameter of the bearing 130. An arcuate third body portion 216 adjoins the latter grooved portion at the narrow end 206, and it has a rounded outer peripheral edge thereat. The third body portion and the corresponding portion on the remaining half together form a circular transverse bearing section having an external diameter less than the diameter of the first and second body portions 208 and 212, and greater than the diameter 65 of the minor diameter grooved section provided by the adjacent grooved portions 214. The recessed edge portions 202b of each half-bearing extend from the outer side of the third portions 216, at the narrow end 206, through such portions and the adjacent grooved portions 70 214, to points in the second body portions 212.

One side wall 182 of the casing 14 is mounted on each bearing 130, being supported on the minor diameter grooved section formed by the portions 214, with its side wall portions around each pivot opening 190 bearing thereon. The surrounding side wall portions are received between the second and third body portions 212 and 216 of each bearing 130, which body portions have greater diameters or thicknesses than the diameter of the pivot openings 190. The casing and the bearings are prevented from moving relative to each other axially of the bearings by this construction, while the casing is pivotally movable circumferentially of the bearings. The interengagement of the casing and the bearings also limits inward movement of the bearings in the support plate mounting openings 52. Outward movement of the bearings is limited by the split rings 134, which extend radially outwardly from the bearings beyond the peripheries of the mounting openings 52. As seen in FIGS. 5 and 11, the bearings provide stops for the drive rod 102 and the clutch spring 122 at respective opposite ends of the drive roller assembly, to insure effective clutching.

Referring especially to FIGS. 5 and 10-15, the drive roller assembly 100, the idler roller assembly 160, and the casing 14 are readily assembled on the frame 12 and disassembled in the following manner. The compression springs 172 are mounted on the spring mounts 56 and inserted into the bores 170 of the holder 166. The idler roller stub shafts 164 are inserted into the respective holder grooves 168, to complete the idler roller assembly.

The support plate mounting openings 52 are arranged to register with the casing side wall pivot openings 190, as illustrated in FIGS. 14 and 15. The narrow end of each bearing 130, at the corresponding ends 206 of the bearing halves, is collapsed on its recessed side edge portions 202b, as illustrated in FIG. 14. The resulting reduction in width or diameter in the bearing end affords sufficient clearance so that the end may be inserted first through a mounting opening 52 and then through a pivot opening 190. The minor diameter grooved section provided by the grooved portions 214 is received in the pivot opening. Similarly, the transverse bearing section provided by the second body portions 212 is received in the mounting opening 52. When the bearing halves are returned to their normal positions, with the planar edge portions 202a of the respective halves lying flat on each other, the bearing is in its assembled position as illustrated in FIG. 15. Both bearings 130 are mounted in the same manner.

The drive rod 102, bearing the tires 110 and having the brake spring 126 mounted thereon, is mounted in the bearings 130 by first inserting the stub shaft 104 of the rod from within the frame into the left-hand bearing as viewed in FIG. 5. The crank shaft 116 then is inserted through the right-hand bearing from without.

The washers 124 with the clutch spring 122 therebetween are mounted on the inner of the crank shaft, which is then inserted into the drive rod cavity 106. The clutch pin 120 is inserted into the hole 118 in the crank shaft, between the washer and spring assembly and the clutch portions 108. The brake spring hook end 128 is hooked over the lower edge of the knife blade 92, between two of its teeth. With the split rings 134 in place on the bearings, the delivery apparatus 16 as assembled and ready for use. The moving parts thereof may be disassembled simply by pulling the clutch pin 120, unhooking the brake spring end 128, and withdrawing the parts. To remove the bearings 130, the split rings 134 are removed, and the bearings are withdrawn through the wall openings by reversing the manipulations illustrated in FIGS. 14 and 15.

The operation of the dispenser 10 may be seen on reference to FIGS. 6-10. With the casing closed, as illustrated in FIGS. 1 and 2, the crank 112 is turned in the clockwise direction, as viewed in FIGS. 7 and 8. The sheet material 174 from the full roll 46, and where applicable, the sheet material 176 from the stub roll 32, previously inserted between the drive roller assembly 100 and the

idler roller assembly 160, is delivered downwardly from between the rollers. The material enters the divergent channel 98 between the knife blade 92 and the upper guide plate section 64, and travels downwardly therein. The direction of movement is changed and the material is guided forwardly in the movement path 86 by the arcuate guide plate section 66 and the guard plate 78. Material is prevented from passing between the bottom of the drive roller assembly and the upper side of the guard plate by the guard fingers 84. The proximity of the idler roller 162 and the guide element shoulder 70 prevent passage of material between them.

Sheet material issues from the dispenser between the lip 68 along the forward margin of the guide plate and the lip 186 on the casing front wall 184. The user grasps the free end of the sheet material, and pulls to place the material under tension across the cutting edge of the knife blade 92 and thereby sever a length of material. The restricted dispensing opening provided by the lips 68 and 186 limits the angles or directions in which the sheet material may be pulled from the knife blade, to those encompassed by the uppermost and lowermost positions illustrated by two types of broken lines 174 in FIG. 7. The user may pull the end upwardly, downwardly, or outwardly, and in any event, the knife blade 92 will effectively sever the material therealong. The construction of the cutting edge to provide short teeth 94 and long teeth 96 spaced along the edge cooperates to provide effective cutting or tearing even at the maximum angle to the blade or lowest position of the sheet material being pulled, i.e., when it is pulled downwardly from the dispenser.

Paper towel dispensers and the like necessarily are mounted in various places where they cannot be watched at all times. Consequently, they are subject to tampering and acts of vandalism by individuals. One troublesome problem is that caused by persons stuffing the material being dispensed back into the dispenser through the movement path 86, so that the material may become wedged in the dispenser, prevent further dispensing, and possibly cause additional fouling. The divergent construction of the channel 98 (FIG. 10) formed with the knife blade 92 functions to minimize the possibility for jamming in this way at a relatively inaccessible location. Thus, the channel widens away from the rollers, so that the force imparted to the sheet material in delivering the same will frequently be sufficient to dislodge paper from within the channel. In addition, as described above, the tension of the idler roller mounting springs 172 is predetermined so that if excessive resistance to delivery should be encountered, the rollers will slip on the sheet material therebetween, and no more material will be forced below the rollers to aggravate the problem.

As the sheet material is used, the size of the remaining roll may be determined from time to time by looking through one of the viewing slots 188. The roll is replaced at any time after it is reduced to a certain size, which is about 2½ inches in diameter or less with one roll of paper toweling in common use, measuring about 6 inches in diameter when full. The stub roll 32 is placed on the bottom wall 18, as shown in FIG. 8, and a full roll 46 is mounted on the yoke assembly 38 with its free end inserted between the rollers with the material from the stub roll. Thereafter, double thickness lengths of material including material from both rolls are dispensed until the stub roll is consumed, when single thickness lengths are dispensed once more.

The invention thus provides significant improvements in a sheet material dispenser and components thereof. The dispenser is simple and economical in construction and use, and effective and reliable in operation. There are but few moving parts, which undergo relatively little wear, and they may be assembled and disassembled easily and rapidly. Multiple functions are performed by structural components which may be fabricated in one piece from sheet metal or other suitable material.

It will be apparent that various changes and modifications may be made in the structure and arrangement of the parts within the spirit and scope of the invention. It is intended that such changes and modifications be included within the scope of the appended claims.

I claim:

1. A dispenser for rolled sheet material which comprises a frame including a base and a support member on each of two opposite sides of the frame, said frame support members each having a mounting opening therein, means for rotatably supporting a full roll of sheet material on said frame and spaced above said base, receptacle means including said base for rotatably supporting a stub roll of sheet material therein below said full roll, sheet material delivery means on said frame including drive roller means and idler roller means receiving sheet material therebetween, said drive roller means having opposite ends journalled respectively in said mounting openings for rotatable support on said frame, resilient mounting means for said idler roller means yieldably holding the latter against said drive roller means to enable the respective roller means to slip on said sheet material when a resistance to delivery is encountered, baffle means interposed between said delivery means and said receptacle means for guiding sheet material from a stub roll in said receptacle means, whereby sheet material may be delivered by said delivery means simultaneously from a full roll and a stub roll supported in said ways, a guide plate adjacent said delivery means for conducting said sheet material in a movement path leading out of the dispenser, a knife blade spaced from said guide plate and the two forming the sides of a channel for movement of sheet material therebetween in a given direction, said channel sides diverging in the direction of movement to forestall vandalic jamming, said knife blade being arranged for the user to pull said sheet material outwardly therefrom in a different direction for severing a length of material thereby, means forming a restricted delivery opening at the outer end of said movement path, the directions in which said sheet material may be pulled from said knife blade being limited thereby to directions in which the material is severed by the knife blade, a casing including a support member on each of two opposite sides thereof, said casing support members each having a pivot opening therein, said ends of said drive roller means being received respectively in said pivot openings to pivotally support said casing on the drive roller means, and a sleeve bearing mounted on each end of said drive roller means disposed in said mounting and pivot openings thereat and interposed between the end and said frame and casing support members thereat respectively, said bearing having a transverse externally grooved section between transverse bearing sections of normally greater thickness than the grooved section and the size of the opening in one of said frame and casing support members, said grooved section being received in the latter opening with said sections of greater thickness disposed externally of the latter support member, said bearing comprising two transversely arcuate longitudinal sections abutting at side edges thereof, said side edges being constructed for collapsing said bearing for inserting said grooved section into the latter opening.

2. In a sheet material dispenser, a frame including a support member on each of two opposite sides thereof, said frame support members each having a mounting opening therein, sheet material delivery roller means having opposite ends journaled respectively in said mounting openings for rotatable support on said frame, a casing including a support member on each of two opposite sides thereof, said casing support members each having a pivot opening therein, said ends of said roller means being received respectively in said pivot openings to pivotally support said casing on the roller means, and a sleeve bearing mounted on the roller means, and a sleeve bearing mount-

ed on each end of said roller means disposed in said mounting and pivot openings thereat and interposed between the end and said frame and casing support members thereat respectively, said bearing having a transverse externally grooved section between transverse bearing sections of normally greater thickness than the grooved section and the size of the opening in one of said frame and casing support members, said grooved section being received in the latter opening with said sections of greater thickness disposed externally of the latter support member, said bearing comprising two transversely arcuate longitudinal sections abutting at side edges thereof, said side edges being constructed for collapsing said bearing for inserting said grooved section into the latter opening.

3. A dispenser for rolled sheet material which comprises a frame, sheet material delivery means on said frame including drive roller means and idler roller means receiving sheet material therebetween, resilient mounting means for said idler roller means yieldably holding the latter against said drive roller means under predetermined tension to enable the respective roller means to slip on said sheet material when a resistance to delivery is encountered, means for rotatably supporting a roll of sheet material on said frame in spaced relation to said delivery means, a guide plate adjacent said delivery means for conducting sheet material therefrom in a movement path leading out of the dispenser, a knife blade intermediate the ends of said movement path and spaced from said guide plate and the two forming the sides of a channel for movement of sheet material therebetween in a given direction, said channel sides diverging in the direction of movement to forestall vandalic jamming, said knife blade being arranged for the user to pull said sheet material outwardly therefrom in a different direction for severing a length of material thereby, and means forming a restricted delivery opening at the outer end of said movement path, the directions in which said sheet material may be pulled from said knife blade being limited thereby to directions in which the material is severed by the knife blade.

4. A dispenser for rolled sheet material which comprises a frame including a base, an upwardly extending guide member on said base including a guide plate surrounded by a baffle, said guide member defining a delivery zone on one side thereof and a receptacle including said base on the opposite side thereof, said receptacle being adapted for containing a stub roll of sheet material rotatably resting on said base, sheet material delivery means on said frame in said delivery zone including drive roller means and idler roller means receiving sheet material therebetween, resilient mounting means for said idler roller means yieldably holding the latter against said drive roller means under predetermined tension to enable the respective roller means to slip on said sheet material when a resistance to delivery is encountered, means for rotatably supporting a full roll of sheet material on said frame in spaced relation above said delivery means and said guide member, whereby sheet material from a full roll and a stub roll supported in said ways simultaneously may be supplied to said delivery means from above for delivery thereby with sheet material from the stub roll being guided thereto by said baffle, said guide plate being disposed adjacent said delivery means therebelow for conducting sheet material therefrom in a movement path leading out of the dispenser, a knife blade intermediate the ends of said movement path and spaced from said guide plate and the two forming the sides of a channel for movement of sheet material therebetween in a given direction, said channel sides diverging in the direction of movement to forestall vandalic jamming, said knife blade being arranged for the user to pull said sheet material outwardly therefrom in a different direction for severing a length of material thereby, and means forming a restricted delivery opening at the outer end of said movement path, the directions in which said sheet ma-

terial may be pulled from said knife blade being limited thereby to directions in which the material is severed by the knife blade.

5. A dispenser for rolled sheet material which comprises a frame including a base, an upwardly extending guide member on said base including a guide plate surmounted by a baffle, said guide member defining a delivery zone on one side thereof and a receptacle including said base on the opposite side thereof, said receptacle being adapted for containing a stub roll of sheet material rotatably resting on said base, sheet material delivery means on said frame in said delivery zone, means for rotatably supporting a full roll of sheet material on said frame in spaced relation above said delivery means and said guide member, whereby sheet material from a full roll and a stub roll supported in said ways simultaneously may be supplied to said delivery means from above for delivery thereby with sheet material from the stub roll being guided thereto by said baffle, said guide plate being disposed adjacent said delivery means therebelow for conducting sheet material therefrom in a movement path leading out of the dispenser, a knife blade intermediate the ends of said movement path and spaced from said guide plate and the two forming the sides of a channel for movement of sheet material therebetween in a given direction, said knife blade being arranged for the user to pull said sheet material outwardly therefrom in a different direction for severing a length of material thereby, and means forming a restricted delivery opening at the outer end of said movement path, the directions in which said sheet material may be pulled from said knife blade being limited thereby to directions in which the material is severed by the knife blade.

6. A dispenser for rolled sheet material which comprises a frame including a base, an upwardly extending guide member on said base including a guide plate sur-

mounted by a baffle, said guide member defining a delivery zone on one side thereof and a receptacle including said base on the opposite side thereof, said receptacle being adapted for containing a stub roll of sheet material rotatably resting on said base, sheet material delivery means on said frame in said delivery zone, said guide plate being disposed adjacent said delivery means therebelow for conducting sheet material therefrom in a movement path leading out of the dispenser, and means for rotatably supporting a full roll of sheet material on said frame in spaced relation above said delivery means and said guide member, whereby sheet material from a full roll and a stub roll supported in said ways simultaneously may be supplied to said delivery means from above for delivery thereby with sheet material from the stub roll being guided thereto by said baffle.

UNITED STATES PATENT OFFICE
CERTIFICATE OF CORRECTION

Patent No. 3,217,953

November 16, 1965

Erwin B. Bahnsen

It is hereby certified that error appears in the above numbered patent requiring correction and that the said Letters Patent should read as corrected below.

Column 9, lines 74 and 75, strike out "and a sleeve bearing mounted on the roller means,"; column 10, line 8, for "mmebers" read -- members --.

Signed and sealed this 20th day of September 1966.
